UNITED STATES PATENT OFFICE.

PETER SZANDULA, OF CHICAGO, ILLINOIS.

DESIGN FOR A CURTAIN-POLE HOLDER.

52,832.

Specification for Design.

Patented Dec. 31, 1918.

Application filed September 3, 1918. Serial No. 252,493. Term of patent 7 years.

To all whom it may concern:

Be it known that I, PETER SZANDULA, a subject of the Emperor of Austria, residing at Chicago, in the county of Cook and State of Illinois, have invented a new, original, and ornamental Design for a Curtain-Pole Holder, of which the following is a specification, reference being had to the accompanying drawing, forming part thereof.

The figure is a perspective view of a curtain pole holder showing my new design.

I claim:—

The ornamental design for a curtain pole holder, as shown.

MR. PETER SZANDULA.
